[57] CLAIM

The ornamental design for a double VHS storage container, as shown and described.

DESCRIPTION

FIG. 1 is a front perspective view of the double VHS storage container showing our new design;

FIG. 2 is a top plan view of the double VHS storage container of FIG. 1, the bottom being a mirror image;

FIG. 3 is a front elevational view of the double VHS storage container of FIG. 2;

FIG. 4 is a rear elevational view thereof; and,

FIG. 5 is a right side elevational view thereof, the left side being a mirror image.
